MEASURING AND DISPENSING ATTACHMENT
FOR A COFFEE CONTAINER

Steven G. Groover, 9944 Cornwall Drive,
Huntington Beach, Calif.

Filed Oct. 19, 1965, Ser. No. 87,589

Term of patent 3½ years

(Cl. D58—26)

FIG. 1.

FIG. 2.

FIG. 3.

FIG. 4.

FIG. 5.

FIG. 1 is a left side elevational view of a measuring and dispensing attachment for a coffee container showing my new design;

FIG. 2 is a front elevational view thereof;

FIG. 3 is a bottom plan view thereof;

FIG. 4 is a top plan view thereof; and

FIG. 5 is a front, right, bottom isometric view thereof.

I claim:

The ornamental design for a measuring and dispensing attachment for a coffee container, substantially as shown.
